W. F. Long INVENTOR.

BY
John D Morgan
ATTORNEY

UNITED STATES PATENT OFFICE.

WILLIAM H. LONG, OF NEW YORK, N. Y.

GRAINER FOR PLANOGRAPHIC PLATES.

1,346,501.

Specification of Letters Patent. Patented July 13, 1920.

Application filed August 18, 1916. Serial No. 115,729.

To all whom it may concern:

Be it known that I, WILLIAM H. LONG, a citizen of the United States, and a resident of New York, in the county of New York and State of New York, have invented certain new and useful Improvements in Grainers for Planographic Plates, of which the following is a specification.

The invention relates to an improved machine for graining plates for planographic printing. Objects and advantages of the invention will be set forth in part herein-after and in part will be obvious herefrom, the same being attained through the instrumentalities pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description serve to explain the principles thereof.

Of the drawings:—

Figure 1 is a top plan of a machine constructed in accordance with the principles of the invention;

Fig. 2 is a vertical section on the line A—B of Fig. 1;

Fig. 3 is a partial section approximately on the line C—D of Fig. 2, and showing other parts in elevation; and

Fig. 4 is a view similar to Fig. 1 but showing a different form of plate holding box.

Referring by way of example to the accompanying drawings, the machine is mounted upon a suitable stationary frame 1, said frame comprising a floor plate 2, and a plurality of upright frame members 3 rising therefrom, and supporting a top frame member or top plate 4. Fixed to or integral with the stationary frame plate 4 are two upwardly projecting journal blocks 5 and 6. Pivotedly mounted for rocking movement upon the blocks 5 and 6 by means of pintles or trunnions 7 and 8, respectively, which pintles are journaled in the blocks 5 and 6, is a frame 9. The frame 9 comprises an inner annulus 10, located within the journal blocks 5 and 6, from which annulus project the pintles or trunnions 7 and 8. This annular portion 10 of the rocking frame

has projecting outwardly therefrom, and preferably radially, spiders 11, 12, 13, and 14, said spiders carrying at their outer ends a rim or annulus 15. Mounted upon the outer side of the rim 15 are a plurality of 60 friction rollers 16, 17, 18 and 19. The entire structure just described is adapted to rock or oscillate in its journal bearings upon the blocks 5 and 6.

Suitable means are provided for rocking or oscillating to and fro the frame 9 just described, and as embodied said means comprise a power shaft 20 mounted in suitable bearings 22 and 23 in the machine frame. The shaft 20 is driven in a suitable manner, 70 as by a variable speed pulley 21. Fixed to the shaft 20 is a crank disk 24, to which is pivotally connected a rod 25. The other end of the rod 25 is pivotally connected by a ball and socket joint 26 to a lug 27, carried 75 by and extending inwardly from the ring 15. Thus as the shaft 20 rotates, there is imparted to the frame 9 a rocking or oscillating motion about its bearings 7 and 8.

A suitable receptacle for the plates to be 80 grained is provided in the form of a box, to the bottom of which the plate is attached, the graining materials acting upon the surface of the plate, due to the motion of the box. In Fig. 1 of the drawings the box is 85 shown of circular form with a flat bottom, and in Fig. 4 the box is shown of substantially rectangular form, with counterweights 29 to produce proper balance. The box 30 has the plate α fastened to the bottom thereof, the side walls 31 of the box serving to keep the graining materials therewithin.

Suitable means are provided for supporting the box so that it will receive the rocking or oscillating motion of the frame 9, 95 and also have rotatory motion substantially about its center, both motions being preferably simultaneous. As embodied, the box 30 has upon the bottom thereof a plate 32 adapted to rest upon the rollers 16, 17, 18 100 and 19, the plate 32 and the box 30 rolling around upon these rollers. At the center of the box the plate 32 has a downwardly projecting portion 33, which is spherically recessed to receive and to rest upon a ball 105 34. The ball 34 in turn rests in a spherical recess 35 in or attached to the top plate 4 of the frame. At or near its periphery the plate 32 is provided with a downwardly extending annular flange 36, from the lower 110

end of which flange extends inwardly a holding lip or plate 37, which extends beneath the rollers of the frame 9. The box 30 with the plate α is thus mounted to rock to and fro with the frame 9 but is free for rotatory motion thereupon and upon the ball 34.

Suitable means are provided for rotating the plate box 30, and as embodied the shaft 10 20 has fixed thereto a bevel gear 45, with which meshes a bevel gear 46 on an upwardly extending shaft 47, which shaft is journaled in bearings 48 and 49 on the machine frame. At its upper end there is fixed 15 to the shaft 47 a pinion 50 meshing with a horizontally disposed gear ring 51. The gear ring 51 is rotatably supported upon the top of the frame plate 4. The ring 51 is kept to center and in place horizontally, 20 while being free to rotate, by suitable means, comprising suitable collars formed on the machine frame.

The gear ring 51 and the box 30 are connected together in a suitable manner, and 25 as embodied there are provided downwardly projecting fingers 52 and 53, fixed to inwardly disposed projections 55, fixed to the plate 37, and conveniently carried by two of the spiders 11, 12, 13 and 14. The fingers 30 52 and 53 project through radially disposed slots 57 formed in the gear ring 51, thereby carrying the plate box 30 and plate α around with the gear ring 51 in its rotatory movement, while permitting the plate box and 35 plate to rock with the frame 9. The rocking and the rotatory movement may be correlated to each other in such manner as to vary and modify the combined motion to

the best advantage in producing a high quality grain for printing. 40

The plate box may be emptied of the marbles and slush by means of a hole closed by a suitable plug or like device.

From all the foregoing it will be understood that a machine has been provided realizing the objects of the invention and the advantages herein set forth, together with other objects and advantages; and it will be further realized that changes may be made from the specific construction herein shown 50 and described without departing from the principles of the invention and without sacrificing its chief advantages.

What I claim as my invention is:

1. A grainer for planographic printing plates including in combination a plate box, and devices for simultaneously rotating and rocking the box. 55

2. A grainer for planographic printing plates including in combination a rocking 60 frame, a plate box mounted upon and rocking with the frame and simultaneously rotating relatively thereto.

3. A grainer for planographic printing plates including in combination a vertically 65 rocking frame, a plate box rocking therewith, and means for horizontally rotating the plate box.

In testimony whereof I have signed my name to this specification in the presence of 70 two subscribing witnesses.

WILLIAM H. LONG.
